United States Patent Office

Des. 218,387

Patented Aug. 18, 1970

218,387

COMBINATION BRUSH, SCRAPER, BOTTLE OPENER AND PURSE

Wiley M. Whitaker, Asheboro, N.C., assignor to New Broom, Inc., Asheboro, N.C., a corporation of North Carolina

Filed Feb. 16, 1968, Ser. No. 11,039

Term of patent 14 years

Int. Cl. D4—01

U.S. Cl. D4—6

FIG. 4

FIG. 1

FIG. 2

FIG. 3

FIG. 1 is a front perspective view of a modified design for a combination brush, scraper, bottle opener and purse; FIG. 2 is a rear elevational view of FIG. 1;

FIG. 3 is a right end elevational view of FIG. 2; and FIG. 4 is a top plan view of FIG. 2.

I claim:

The ornamental design for a combination brush, scraper, bottle opener and purse, as shown.
